APPARATUS FOR SUBJECTING SHOES AND
OTHER ARTICLES TO PRESSUREOtto Habicht, Frankfort-on-the-Main, Germany,
assignor to Compo Shoe Machinery Corpora-
tion, New York, N. Y., a corporation of Dela-
wareApplication November 1, 1928, Serial No. 316,515
Renewed November 9, 1934

24 Claims. (Cl. 12—36)

My present invention relates to apparatus for exerting pressure on shoes and other articles. The improved apparatus has been designed primarily for the purpose of applying pressure for the purpose of securing the outer sole of a shoe to the shoe with the aid of a suitable glue or cement. The invention however, is also applicable with the object of applying a finishing or polishing pressure to a shoe, or for forming or molding a shoe prior to sewing it. The invention may also be used in connection with other articles, being applicable generally whenever pressure is to be exerted for the purpose of connecting two parts, or forming an article, or applying a polish or another finish to such article. One of the objects of my invention is to provide a simple and improved apparatus of the kind indicated above, which in its preferred form affords special facilities for applying pressure successively to a number of articles brought into the working position by a traveling conveyer. Other objects of my invention will appear from the detailed description following hereinafter.

Various embodiments of my present invention are shown in the accompanying drawings in which Fig. 1 is a side elevation showing one form of my invention; Fig. 2 is a detail end elevation of a portion of the machine, partly in section; Fig. 3 is a plan view of the machine portion shown in Fig. 2, with parts in section; Fig. 4 is a separate plan view of a cushion employed in connection with the machine or apparatus shown in Figs. 1, 2 and 3; Fig. 5 is a longitudinal section of the blank from which such cushion is formed; Fig. 6 is a partial plan view illustrating certain characteristics hereinafter referred to; Fig. 7 is a view similar to Fig. 2, representing another form of construction; Figs. 8, 9 and 10 are detail elevations showing three additional embodiments of my invention; Fig. 11 is a sectional detail of the construction shown in Fig. 10; Fig. 12 is a diagrammatic side elevation of another form of my invention; Fig. 13 is a side elevation illustrating a form of my apparatus in which inflatable cushions are used; Fig. 14 is a partial end elevation of the apparatus shown in Fig. 13, and Fig. 15 a partial plan view thereof; Fig. 16 is a side elevation of another form of my apparatus, likewise employing inflatable cushions; Figs. 17 and 18 are a partial end elevation and a partial plan view respectively of the apparatus shown in Fig. 16; Fig. 19 is a partial side elevation of a third form of my apparatus employing inflatable cushions; Fig. 20 is a detail section of a valve employed in connection with apparatus

such as shown in Figs. 13 to 19, and Fig. 21 is an end elevation of another form of my invention.

In Figs. 1 to 5, I have shown an endless traveling conveyer composed of links connected with each other loosely to enable the conveyer to bend properly and in a longitudinal direction, that is, circumferentially of rotary guides or supports with which certain portions of the conveyer are engaged. In Fig. 1, the left hand portion or bend of the conveyer passes around a polygonal support or drum 30, here shown as having twelve sides, while the right hand portion of the conveyer engages a cylindrical drum or roller 31. The latter is represented as of much smaller diameter than the drum 30, and the lowermost portions of the drums 30, 31, are arranged at the same level, the centers or shafts 32, 33 of said drums being therefore at different levels. With this arrangement, the lower run of the conveyer becomes horizontal, while its upper run is inclined downwardly from the upper portion of the drum 30. This particular inclination presents certain important advantages, as will be explained below, and it will be obvious that such inclination may be obtained in other ways, and does not require, as an indispensable condition, that the two drums be of different diameters, and that the lower conveyer run be horizontal, although such arrangement presents certain practical advantages. The drums are journaled in suitable standards 34 and 35 respectively. Any suitable means are provided for bringing the shoes or other articles to be treated, to the conveyer portion resting on the uppermost part of the drum 30. In Fig. 1, I have illustrated a horizontal conveyer belt 36 (of the endless type) for bringing the articles into a position adjacent to the uppermost portion of the drum 30, and another horizontal endless conveyer belt 37 for carrying the articles away after they have been exposed to pressure. Any suitable mechanism is provided for operating the three conveyers. The conveyer 37 might travel continuously in the direction indicated by the arrow, but the conveyer engaging the drums 30, 31 should travel intermittently, and preferably the feeding conveyer 36 also should receive an intermittent motion. As an example of a simple mechanism for operating said three conveyers, I have indicated a ratchet wheel 38 rigid with the drum 30 and engaged by a pawl 39 which is pivoted at 40 to a rod 41 mounted to slide lengthwise (and also to have a slight swinging movement) in a stationary guide 42, a spring 43 tending to force the pawl 39 toward the ratchet wheel 38. The lower end

50

55

of the rod 41 is pivotally connected at 44 with a pedal 45 fulcrumed at 46. A spring 47 tends to restore the pedal 45, and with it the rod 41 and the pawl 39, to their upper position shown in Fig. 1, the pedal then engaging the upper stationary stop 48. By depressing the pedal until it engages the lower stationary stop 49, the pawl 39 will be caused to give the drum 30 exactly one-twelfth of a revolution. Suitable means, such as a spring 50 engaging the drum 30, may be employed to hold the drum in proper position so that it will always come to a stop with its uppermost side horizontal, and thus relieve the operator of the necessity for adjusting the drum to such position. With the drum 30 are also rigidly connected pulleys or sprocket wheels 51 which through the medium of belts or chains 52, 53 and other pulleys or sprocket wheels 54, 55 operate the rollers 56, 57 engaged by the conveyers 36, 37 respectively. While the connection from the drum 30 to the conveyers 36, 37 might be permanent or positive, so that these two conveyers would at all times move in unison with the drum, I prefer to provide means whereby either one or both of said conveyers may be allowed to remain stationary during the movement of the drum 30. For instance, as indicated in Fig. 1, the connection of each sprocket wheel or pulley 54, 55 with the respective roller 56 or 57 may be controlled by a clutch 58 or 59 respectively, of any well-known or approved character, the clutch-shifting levers being shown at 60 and 61 respectively. Normally, the clutches would be in such a position that the wheels or pulleys 54, 55 would rotate in unison with the respective rollers 56 and 57.

It will be understood that when the pedal 45 is released, the spring 47 will restore the parts to the position shown in Fig. 1, the spring 43 allowing the pawl 39 to swing outwardly on the pivot 40 as the pawl rides up on the inclined face of one of the ratchet teeth, and swinging said pawl into the next notch of the wheel 38 as soon as the pawl rises beyond the point of a ratchet tooth.

Figs. 1, 2 and 3 illustrate the following construction of the main conveyer engaging the drums 30 and 31: Said conveyer is composed of links each having a base or body 62, shown as of rectangular shape, on which is provided a last support. In the embodiment shown, said support comprises a heel portion 63 rigid with the base or body 62, and an adjustable toe portion 64, which may, for instance, be pivoted to the heel portion, as at 65, to swing about an axis ranging lengthwise of the conveyer, the adjustment being effected in any suitable manner, as by means of a screw 66 threaded into the base or body 62 and in proper engagement with the toe portion 64, a milled head 67 being shown on said screw as a means for operating it. To each of the conveyer links (generally made of aluminum) is pivoted to swing about an axis 68 which extends lengthwise of the conveyer and parallel to the pivot 65 of the same link, a bail comprising two side members 69 each having one of its ends at the pivot axis 68, while the other ends are connected by a cross member 70 the purpose of which will be explained hereinafter. Preferably means, such as a spring 71, are provided which tend to swing 70 or fold the bail 69, 70 toward the base or body 62.

Adjacent links of the main conveyer are connected in a manner to provide their required relative mobility. Each of the joints or connections is shown as comprising a central lug 72 rigid with the base 62 of one link and a double lug or fork

73 rigid with the base 62 of the adjoining link, and embracing the said lug 72. Through these lugs 72, 73 extends a connecting pin 74 transverse to the conveyer, and in the general plane thereof, the several pins 74 remaining parallel to the shafts 32, 33, in the particular embodiment shown in Figs. 1, 2 and 3. Each pin 74 is shown as fitted closely into the lug 72 and quite loosely into the other lug, 73, the latter having openings 75 which afford considerable play, see Fig. 3. The pin 74 may fit into the lug 72 so tightly that it will be rigid therewith (and this is preferred), although there would be no serious objection if the pin 74 could turn about its own axis in the lug 72.

Each of the bases 62 is also shown as provided with a rigid projection or rib 76 extending in a transverse direction, substantially parallel to the shafts 32, 33, and adapted to fit into one of a series of twelve corresponding recesses or sockets 77 on the drum 30. I thus ensure a proper automatic positioning of each conveyer link relatively to the side of the drum 30 with which it comes into registry and engagement during the travel of the conveyer and the rotation of the said drum.

The following means have been indicated in Figs. 1, 2 and 3 to obtain a proper guidance of the conveyer runs between the two drums 30, 31: The base 62 of each conveyer link is provided, at its ends (short sides of the rectangular links), with projections adapted to travel along suitable stationary guides or tracks. For instance, such guides may be grooved or forked, as shown at 78, to embrace the projections 79 extending from the link bases 62. Preferably the guides would be made with flaring entrance portions 80 to ensure a proper passage of the said projections into the guides.

In connection with the last supports 63, 64 I employ a cushion. In Figs. 2 and 3 I have shown a molded cushion 81 engaging the upper or outer surface of the last support 63, 64. In detail, this cushion may be constructed as described hereinafter with reference to Figs. 4 and 5. The cushion 81 may be placed loosely on the support 63, 64 at the proper time, or it might be secured to said support. Fig. 2 indicates at A an outer sole, at B the lasted shoe with which it is desired to connect said sole by pressure, and at L the last on which such shoe is fitted or stretched, in the well-known manner.

In connection with the parts described above, I employ a presser bow which may have the general shape of those shown in my United States Letters Patent No. 1,445,942 dated February 20, 1923 and No. 1,473,038 dated November 6, 1923, such bow, however, being constructed with certain novel features to enable it to co-operate properly with my present new apparatus and particularly with the bail 69, 70. The presser bow illustrated comprises a body 82 to the heel end of which is pivoted at 83 a member or block 84 provided with a pin 85 adapted for insertion into a socket 86 in the heel portion of the last L; on the toe portion of the bow body 82 is mounted a slide 87 movable lengthwise and adapted to bear, with its free end, on the forward or toe portion of the last. These features of the bow, which are also disclosed in the patents mentioned above, enable the presser bow to be adjusted to fit lasts of different sizes and shapes. One of the novel features of the presser bow shown in my present application consists in providing its body 82, on the side opposite the block 84 and the slide 87, with a holding portion 88 of such shape that when the presser bow is in operative position, such por-

tion will be eccentric to the pivot 68 of the bail 69, 70 and adapted for engagement with the transverse connecting member 70 of such bail. Preferably this holding portion 88 is made with 5 teeth or notches, as shown, to prevent accidental movement of the bail when engaged with said portion.

In addition to the features described above, the presser bow has, on its body 82, an engagement surface 89 adapted for contact with a suitable movable member to exert pressure on the said body toward the last support 63, 64. Various constructions of pressure-exerting mechanism may be adopted; in Fig. 1 I have indicated, 10 as an example of a mechanism which will accomplish the desired effect, a stationary hydraulic cylinder 90 in which a plunger or piston 91 is movable vertically, in the proper path to come into and out of engagement with the engagement 15 surface 89 of the pressure bow body 82 when the latter is in the position shown in Fig. 1 in connection with the uppermost (horizontal) link of the main conveyer. At 92 I have indicated a pipe for conveying the medium under pressure (say 20 water, although air might be used) to the cylinder 90 from a suitable source, the connection being controlled by a valve 93 which the operator can actuate in any appropriate manner, preferably by means, such as a knee lever 94, which 25 leaves both of his hands free.

It will be noted that as the main conveyer passes around the drum 30, the conveyer portion or link immediately to the left of the horizontal link which is in the uppermost or working position, will be inclined downwardly from said horizontal link, and the same remark will apply to the link which is immediately to the right of said horizontal link. Thus the two last supports and their bails 69, 70 on the two links which are 30 to the left and to the right respectively of the said temporarily uppermost link, will be as it were spread away from it, or diverge upwardly as shown clearly in Fig. 1, thus affording an ample space for the transfer of articles to and 35 from said temporarily uppermost link, and also gaining more room for the overhead pressure-exerting mechanism. The drum 31, working in conjunction with the conveyer and with the drum 30, constitutes directing means for causing the 40 links at each side of the one that is in the working position (uppermost link in Fig. 1) to diverge from each other and thus facilitate access to the link that is in the working position.

The operation may be as follows: From the 45 supply conveyer 36 (or from any other place) the operator takes an unfinished shoe B mounted on its last L, and applies to such shoe and to the outer sole A (which he may take from the conveyer 36 or from a table or magazine, not shown). 50 a layer of suitable glue or cement to connect said sole with the lasted shoe. I prefer to use certain types of glue or cement which have the property of becoming very permanent and insoluble upon the application of heat, but other kinds of 55 glue or cement may be employed. The lasted shoe B with the outer sole A thereon is then placed in proper position on the cushion 81 of the main conveyer link which at that time engages the uppermost portion of the drum 30. 60 As has been stated above, such cushion may be secured to the last support 63, 64, or the cushions 81 may be loose, in which event the operator would also have to take a cushion from a stack or other supply at the time of preparing 65 the apparatus for a pressure-exerting operation.

In any event, when a cushion 81 is in proper position on the last support 63, 64 of the uppermost link of the main conveyer (which is stationary at that time) and a lasted shoe B with its outer sole A is in position on such cushion, the operator takes one of the presser bows (say from a table, not shown) and applies it to the last L as shown in Fig. 2. This brings the engagement surface 89 of the presser bow body 82 into registry with the plunger 91, which at that time 10 is in its raised position. The operator then actuates the knee lever 94 to admit the pressure medium from the pipe 92 to the cylinder 90, thus forcing the plunger 91 down against the presser bow, and thus forcing the last L with the shoe 15 B downwardly against the outer sole A, the cushion 81 and the last support 63, 64 serving as a backing or abutment, since the last support 63, 64 can not move downwardly, as it rests on the temporarily stationary drum 30. While the parts 20 are thus under pressure, the operator swings the bail 69, 70 up to bring its transverse member 70 into engagement with the holding portion 88, as shown best in Fig. 2. He then releases the knee lever 94, thereby causing the plunger 91 to return to its normal upper position (under the influence of a spring or by any other well-known or approved means, not shown). It will be understood that the bail 69, 70, by its engagement 25 with the presser bow body 82, will maintain the lower portion of the lasted shoe B, the outer sole 30 A, and the cushion 81 under compression.

Thereupon the operator gives the drum 30 a partial rotation sufficient to bring the next link of the main conveyer into the working position. 35 This may be accomplished by the mechanism described above in connection with the pedal 45. I desire it to be understood, however, that a mechanism operated by foot power has been selected chiefly for illustrative purposes, on account of simplifying the drawings, and that operating mechanisms of various other kinds may be used in practice.

With the arrangement illustrated, each partial rotation of the drum 30 will also impart a corresponding movement to the feeding conveyer 36 and to the delivery conveyer 37, since the clutches 58, 59 are normally in their operative or "thrown-in" position. The conveyer 36 will thus bring another lasted shoe within convenient reach of the 50 operator, who may be standing or seated at 95. He then repeats the operations described above. Thus by a succession of intermittent movements of the drum 30, the feeding conveyer 36, and the main conveyer passing over such drum, with the 55 proper assembling, pressure, and pressure-holding (bail 69, 70) operations performed while the conveyers are stationary, the operator will gradually load all the links of the main conveyer in the manner set forth above. Finally, the link which 60 was loaded first will again reach its original position, at the top of the drum 30. By this time, the glue or cement will have dried or set sufficiently to permit the shoe to be removed. For this purpose, the operator throws the bail 69, 65 70 out of engagement with the presser bow, and then removes the presser bow and the shoe from the main conveyer, separates the presser bow from the last, and places the lasted shoe, with the outer sole A now firmly connected therewith, 70 on the delivery conveyer 37, which carries such article away in the direction indicated by the arrow. Should the operator find it difficult to disengage the bail 69, 70 from the presser bow body 82, he can simply actuate the knee lever 94 once 75

more to force the plunger 91 and the said body 82 down and thereby release the bail from the upward pressure of the cushion 81. The clutches 58, 59 may be thrown out whenever it is desired to rotate the drums 30, 31 without operating the conveyors 36, 37, for instance if the operator discovers that one of the articles is defective and wishes to take it out, after such article has left the working station.

10 In some cases, the temperature of the room in which the apparatus is placed may be sufficient to bring the glue or cement to the proper condition by the time the shoe returns to its original position at the top of the drum 30. In other cases, 15 it may be found desirable to provide for the application of heat. For instance, as indicated in Fig. 1, a portion of the conveyer path may extend through a channel or housing 96 constituting a heater, say by passing hot air or hot gases therethrough from 97 to 98. Other means may be adopted for heating portions of the main conveyer, or the entire conveyer, or even the whole machine. It will be understood that the main conveyer may be of considerable length, and may 20 have its portions between the final bends (at the drums 30, 31) either horizontal and inclined as shown, or placed in other convenient ways, according to the space available. The particular flexible connection establishing universal joints 25 between the links of the main conveyer enables the conveyer (in addition to its usual longitudinal bending) to bend laterally if considerations of space etc. should make this appear desirable; thus, the plan view Fig. 6 illustrates guides 78' having 30 a lateral curvature to lead the conveyer to one side at a certain portion of its path. 35

It will be noted that the toe portion 64 of the last support is nearer to the operator's stand 95 than the heel portion 63, so that the toe of the 40 last and of the shoe will be toward the operator as he places them on the cushion 81. This affords the operator a clearer vision and greater facility for placing the shoe accurately on the last support than the usual practice in which the heel 45 of the shoe is toward the operator.

Figs. 4 and 5 illustrate a suitable and very satisfactory way of making a molded cushion, and the cushion 81 referred to above may be one produced in this manner. Fig. 5 shows a longitudinal section of the blank from which the cushion is formed, said blank having a top layer 99 preferably made of leather or like material, a lower layer or foundation 100 made of pulp board or the like, and an intermediate layer 101 made of a material, for instance felt, which is more elastic or compressible than the other two; in fact, the cushion effect is due largely to this intermediate layer. The blank is cut to the desired outline (see Fig. 4), and its three layers are glued or cemented together. By a suitable molding operation, the blank is given the final shape of the molded cushion, for instance such as illustrated for the cushion 81. The simplest way of conducting this molding operation consists in placing the cut blank on one of the links of the main conveyer while such link is directly under the plunger 91, the blank being preferably first moistened so that it will be molded more readily. Then the proper last L (without any shoe or sole) is placed on the leather layer 99, the presser bow is applied to such last in the manner described above, and the plunger 91 is depressed to engage the presser bow body 82 and compress the cushion between the last L and the last support 63, 64. The bail 69, 70 may be employed for maintaining the pres-

sure as long as desired. Thus the cushion will be molded not only on its lower surface, to conform to the last support 63, 64, but also on its upper surface, in which there will be produced a depression or recess 102 corresponding to the shape of the last bottom. A molded cushion thus formed will enable a last L, with the unfinished shoe B and the outer sole A, to be placed very accurately on the last support 63, 64. 5

It will be seen that the operator has ready access to that link of the main conveyer which rests on the uppermost face of the drum 30, but the other portions of said conveyer are comparatively inaccessible and largely covered and protected by the supply conveyer 36 and the delivery conveyer 37. 10 15

In Fig. 7 I have shown an arrangement for heating the several cushions continuously, at every portion of the main conveyer. The detail construction of this cushion 81' may be exactly 20 as explained with reference to Figs. 4 and 5, except that a resistance wire or heating wire 103, of well-known character, would be embedded in the cushion, preferably between the layers 99 and 101 thereof. The terminals of the heating wire 25 of the same cushion would be connected to contacts 104, 105 respectively, carried by the link projections 79, and in sliding engagement, during the movement of the conveyer, with stationary contact rails 106, 107 respectively, which may be 30 secured to the stationary guides 78'.

In Figs. 8 to 11 I have shown three different pressure-exerting and holding arrangements which may be substituted for the one illustrated by Figs. 1 to 7. According to these three arrangements, the plunger 91 does not come into contact with the engagement surface 89 of the presser bow body 82, but with an arm movable toward and from said surface. In Fig. 8, the arm 108 is movable toward and from the base 62 of the conveyer link, along a bar 109 which is rigidly connected with the link base 62 and extending vertically at the time that such link is in the "working" position, at the uppermost portion of the drum 30. The bar 109 is of rectangular or like section, and the opening in the arm 108 through which said bar passes, is of corresponding shape. The arrow in Figs. 8, 9 and 10 indicates the point at which the plunger 91 is arranged to engage the movable arm. In Fig. 8, this point is half way between the bar 109 and that portion of the arm 108 which is adapted for contact with the engagement surface 89. When the plunger 91 moves down, both ends of the arm 108 move downward equally, and the action on the presser bow, the last, shoe, and cushion is the same as described above. When the plunger 91 is released and moves up, the upward pressure of the cushion tends to swing the arm 108 about its apertured end as a temporary fulcrum, and thus the arm 108, instead of sliding upward on the bar 109 and following the plunger, will bind at the guided end, and will remain stationary in a position in which it prevents upward movement of the presser bow and thus holds the shoe, the outer sole and the cushion under compression. Thus

sole, and the cushion under compression. Thus the arm 108 also acts as a pressure holding member and in this respect performs the same function as the bail 69, 70. This bail and the holding portion 88 cooperating therewith, are therefore dispensed with in the construction illustrated by Fig. 8, and the same remark will apply to the arrangements shown in Figs. 9, 10, and 11. The release of the arm 108, when it is desired to remove the article, can be effected by simply pressing 75

ing or knocking upwardly against the eye of the arm, adjacent to the bar 109. In Fig. 9, the center of the arm 108' is adapted for contact with the engagement surface 89 of the presser bow body 82, while both ends of said arm are guided for sliding movement along parallel bars 109' rigidly connected with the link base 62. In this case, as the upward pressure or reaction of the cushion, after the plunger 91 has been retracted upwardly, is exerted against the central portion of the arm 108', there will be no such automatic binding or pressure-holding action as has been described above in connection with Fig. 8. I have therefore provided, in Fig. 9, special means, to be actuated by the operator, for locking the arm 108' to the bars 109' at the time that the plunger 91, acting against the central portion of said arm, has been forced down to the desired extent. The locking means shown in Fig. 9 consist of two screws 110 passing through the eyes at the ends of the arm 108'. These screws are loose or inactive until the plunger 91 has been forced down fully; then while the plunger is in its lowermost position, the screws are tightened to lock the arm 108' so that upon the release of the plunger pressure, said arm will continue to hold the article under pressure until the screws are loosened when it is time to remove the article. In Figs. 10 and 11, the bar 109'', rigid with the link base 62, is provided with rack teeth facing toward said base, while the arm 108'' carries a spring-pressed pawl 111 having a handle 112 for withdrawing such pawl against the action of its spring. It will be readily understood that when the plunger 91 forces the arm 108'' downwardly, the pawl 111 will act automatically as a locking member to prevent upward or return movement of the arm upon the upward or return movement of the plunger. The release of the arm 108'' is effected by the operator pulling on the handle 112 to remove the pawl 111 from engagement with the bar 109''. While Figs. 10 and 11 illustrate a rack and pawl arrangement in connection with a short bar guided only at one end, corresponding to Fig. 8, it will be obvious that such rack and pawl arrangement might be used (in duplicate) in connection with a long bar guided at both ends, corresponding to Fig. 9, such rack and pawl arrangement then taking the place of the set screws 110.

While in the construction indicated in Fig. 9 the operator must attend to the locking of the arm 108' in its pressure-holding position, the two constructions shown in Figs. 8, 10 and 11 will accomplish such locking automatically.

The arrangement shown in Fig. 1 provides a single station at which a workman carries out the operation of applying pressure. The arrangement of the conveyer can very readily be modified in such a way as to provide a plurality of working stations. An example of such an arrangement is shown diagrammatically in Fig. 12, where the main conveyer is shown in connection with two drums 30', 31' of like diameter, the upper run of the conveyer being allowed to sag so that the favorable working conditions described in connection with the drum 30 of Fig. 1 will be present equally at the upper portions of both drums 30', 31'. Thus one workman may be stationed adjacent to the drum 30', and another at the drum 31'. It will be understood that the details of conveyer links, pressure and holding mechanism, and accessories such as feeding and delivery conveyers (all of which have been omitted from Fig. 12), may be constructed in accordance with the other figures of the drawings. The drum or

roller 31 or 31' constitutes directing means cooperating with the main conveyer to cause the links at each side of the one that is in the working position, to diverge from each other and facilitate access to the link which is in said working position. 5

In the forms of my invention described above, pressure is exerted on the presser bow toward the base of the conveyer link. My invention however is not restricted to this particular way of exerting pressure, and I will now describe embodiments of my invention in which the cushion interposed between the last support 63, 64 and the article to be treated, is inflatable or expandable for the purpose of producing the desired pressure, the body 82 in this case serving as an abutment or backing against which the article is pressed upwardly, that is to say, in a direction away from the base 62 of the link. 10 15

The first construction of this type is shown 20 in Figs. 13, 14, and 15. The drum 30, conveyer links, last, presser bow, and bail shown in these views may be substantially like those shown in Figs. 1, 2, and 3. The cushion 81'' instead of being solid as in the constructions first described 25 above, is hollow and adapted to receive a fluid under pressure, to expand or inflate such cushion, which may be made of rubber. This fluid is generally air. Two of the links of the conveyer do not, like the other links, carry last supports and 30 their adjuncts, but one of these two links carries an air compressor 113 (of any suitable construction) and an electric motor 114 for operating it, such compressor and motor being shown as mounted on the same shaft. The other link, preferably adjacent to the first, carries an air tank 115, preferably provided with a heater which may consist of a resistance or heating coil disposed in a lining or jacket 116 of said tank. Electric current for the operation of the heating coil and 35 of the electric motor 114 is supplied to the wires 117 on the conveyer in any suitable manner, for instance by means of fixed and sliding contacts which may be of the same character as those described in connection with Fig. 7. Along the 40 entire main conveyer extend two endless flexible conduits 118, 119 one of which is a return conduit in permanent communication with the suction port of the compressor 113, as by means of a connecting pipe or hose 120. This same conduit 45 118 has individual connections with the interior of the several cushions 81'', but these individual connections are controlled by valves 121 spring-pressed or otherwise constructed in such a manner that they will open from the cushion toward 50 the return conduit or suction conduit 118 only when the pressure within the cushion exceeds a predetermined amount, for instance 60 lbs. The delivery port of the compressor 113 is connected 55 with the tank 115 by a pipe or hose 122, and the outlet of the tank is connected by a pipe or hose 123 with the conduit 119, these connections affording a permanently open communication. It will be understood that the conduits 118, 119 and 60 all the parts mentioned above in connection 65 therewith are secured to the main conveyer to travel in unison therewith. Each of the cushions 81'' has a connection 124 leading to the pressure conduit 119, and a valve or cock 125, with a handle 126, is associated with each of these connections 124. Fig. 20 illustrates a detail of this valve; in one of its positions, said valve places the interior of the cushion in communication with the pressure conduit 119, so that air from said conduit will pass into the cushion to inflate it; in 70 75

the other position, the valve 125 places the interior of the cushion in communication with the outside air.

Initially, the valves 125 are in the last-mentioned position, so that the cushions 81'' are deflated. The operator places a lasted shoe with outer sole and a presser bow in position on the cushion of one of the conveyer links, substantially as described above in connection with the other forms of my invention. Then the bail 69, 70 is swung up into position above the holding portion 88 of the presser bow body 82, and thereupon the operator throws the handle 126 of that link into the position which causes the cock 125 to admit air under pressure into the cushion of that link. This cushion being thus inflated (the valve 121 remaining closed until a proper pressure is built up) will press upwardly, the presser bow and the lasted shoe forming a stationary backing against which the outer sole is pressed by the expanding cushion. The result will be the same as in the construction described above. It will be noted that the compressed air is heated, which not only increases its pressure, but is of benefit in assisting the setting of the glue or cement. When the shoe held under pressure has made a complete circuit with the intermittently advanced conveyer, the operator throws the valve or cock 125 into the position in which the interior of the cushion 81'' communicates with the atmosphere. Air will then rush out from this particular cushion, deflating it so as to allow the article to be removed.

Another example of a construction employing inflatable cushions 81'' is shown in Figs. 16, 17 and 18. Here the motor-compressor 113', air-storage tank 115', and air-heater 116' (of any suitable construction) are stationary instead of traveling with the main conveyer. The outlet pipe 123' is connected with a channel 32' in the drum shaft 32, and this channel in turn communicates with a plurality of radial channels arranged in hollow spokes 127 (three such spokes being shown, at equal intervals). At the outer end of each of these spokes, I provide a valve 128 which will close automatically under normal conditions, but will open automatically when brought into cooperative relation with another valve as set forth hereinafter. For this spoke valve, I may use the well-known construction which is found in automobile garages at the end of the hose used for supplying compressed air to tires. The continuous pressure conduit 119' is provided with valves 129 in proper positions to come in successive contact with the spoke valves 128. These valves 129 may be of the same construction as the valves of automobiles tires. The suction conduit 118' has similar valves 129' adapted to co-operate with spoke valves 128' of the same character as the spoke valves 128. One of the three suction spokes is shown at 127' (Fig. 17) and its interior communicates with a longitudinal channel 32'' of the shaft 32, which by means of the return pipe 120' communicates with the suction port of the compressor 113'. The suction conduit has individual valved connections 121 with the several inflatable cushions 81'', in the same manner as in Figs. 13, 14, and 15. These cushions also have cocks or valves 125' of the same character as those shown in Fig. 20, to connect the individual cushions either with the outside air or with the pressure conduit 119'; but instead of being operated by separate handles, as in Figs. 13, 14, and 15, these valves are actuated directly by the swinging of the respective bails 69, 70, the plug of the valve con-

stituting one of the bail pivots. The operation is thus simplified, since swinging the bail to its pressure-holding position will automatically cause the cushion to be inflated, whereas folding the bail toward the link base 62 will cause the cushion to be deflated.

The two constructions shown in Figs. 13 to 18 provide for a circulation of (heated) air, that is to say, the air passing out of a cushion through the relief valve 121 will be returned to the suction port of the compressor. In Fig. 19 I have illustrated a modification similar to the construction shown in Figs. 16, 17 and 18, in which any air passing out of a cushion through the relief valve 121 will be discharged simply into the atmosphere, this modification therefore dispensing with the suction conduit and with the valves and other connections between such suction conduit and the inlet of the compressor. The latter therefore in this modification will draw air from the atmosphere, and not from the cushions. The heated air escaping from the cushion whenever its relief valve 121 is open, will in this modification come in contact with, and flow around, the adjacent parts of the apparatus, and will exert a beneficial action by keeping these parts warm and assisting in causing the glue or cement to set.

In the description given above, it has been assumed that the main conveyer is of a length exceeding the circumference of the drum 30 (or the drums 30', 31'); thus, if the drum has twelve faces or sides, as in Fig. 1, it has been assumed that the conveyer is made with considerably more than twelve links. I desire to point out, however, that in the case of the apparatus shown in Fig. 1, a conveyer having only twelve links might be used; this conveyer would, of course, simply rotate in unison with the drum 30, the drum 31 being inactive. The purpose would be to start the apparatus with the relatively low initial capacity of twelve successive "loadings" or "workings", to meet the modest requirements of a small factory. Then, if with improving business the user desired to increase the capacity of the apparatus, he would not need to buy a new machine, but only to add the proper number of links to his main conveyer and pass the latter over both drums 30, 31 in the manner shown in Fig. 1.

As stated at the beginning of this specification, my invention is applicable to many uses other than the one described specifically.

It will be noted from Figs. 14, 15, 18 and 19 that the air under pressure is admitted to the central portion of the cushion so that such air will become evenly distributed, and so that there will be no tendency of the air to act chiefly on one side and to shift the shoe or other article.

For the sake of greater clearness in illustration, I have shown the pipes or conduits 118, 119 and 118', 119' farther apart than they would be located in practice, where they would be placed close together near the longitudinal center of the conveyer.

I may provide a hook or other handle 39' on the pawl 39 to enable the operator to release the ratchet wheel 38 entirely by withdrawing the pawl 39 therefrom, so that the operator may shift the conveyer rearwardly or forwardly, as he may desire, thereby facilitating the return of any article to the "working" position.

In Fig. 21 I have shown in a somewhat diagrammatic fashion another form of my invention, in which the construction is substantially like that illustrated by Figs. 1 to 3, with this difference—that the main conveyer instead of being

transversely horizontal as shown in Fig. 2, is given a downward inclination toward the position 95 at which the operator is stationed. This presents the advantage of enabling the operator to see 5 much better the entire upper portion of the conveyer and especially the conveyer link which is in the working position at the uppermost portion of the drum 30a. The construction also enables the operator to reach more readily into the parts 10 of the machine near the working position and brings these parts nearer to him than when the conveyer is transversely horizontal.

I claim:

1. An apparatus for subjecting articles to pressure, comprising a movable series of article supports hingedly connected with each other after the manner of chain links, means for imparting motion to said series of supports to bring the individual supports successively to a working position, a removable presser element adapted to be placed on the side of the article opposite to the support, an adjustable pivoted bail for connecting said presser element with the article support or freeing it therefrom, and pressure mechanism 25 adapted for co-operation with each of said article supports and with the presser elements.

2. An apparatus for subjecting articles to pressure, comprising a movable series of article supports hingedly connected with each other after the manner of chain links, means for imparting motion to said series of supports to bring the individual supports successively to a working position, a removable presser element adapted to be placed on the side of the article opposite to the support, a pivoted bail mounted to swing transversely of the path of said series of supports, for connecting said presser element with the article support or freeing it therefrom, and pressure mechanism adapted for co-operation with each 40 of said article supports and with the presser elements.

3. An apparatus for subjecting articles to pressure, comprising a conveyer composed of movably connected links, a polygonal rotatable drum 45 engaged by said conveyer and adapted to bring the links thereof successively into a working position, and pressure mechanism adapted for co-operation with said links while they are in contact with said drum.

50 4. An apparatus for subjecting articles to pressure, comprising a conveyer composed of movably connected links, a rotatable drum engaged by said conveyer and adapted to bring the links thereof successively into a working position on said drum, directing means co-operating with the conveyer to cause the links at each side of the one that is in the working position, to diverge from each other and facilitate access to the link that is in said working position, and pressure mechanism adapted for cooperation with said links and arranged to exert pressure at a link 55 which is in working position on the drum.

5. An apparatus for subjecting articles to pressure, comprising a conveyer composed of movably connected links, article supports carried by said links and each consisting of relatively movable portions to enable them to fit different articles, a removable presser element adapted to be placed on the side of the article opposite to the respective support, an adjustable pivoted bail for connecting said presser element with the article support or freeing it therefrom, and pressure mechanism adapted for co-operation with said links.

6. An apparatus for subjecting shoes and like 75 articles to pressure, comprising a conveyor chain

composed of movably connected links, a base on individual links, a heel support rigid with said base, a toe support pivoted to said base about an axis ranging lengthwise of the conveyor chain, and pressure mechanism adapted for cooperation with said supports. 5

7. An apparatus for subjecting articles to pressure, comprising a conveyor chain composed of connected links, an article support on individual links, a presser element adapted to engage the article on the side opposite to the support, a bail pivoted to said support about an axis ranging lengthwise of the conveyor chain and adapted to engage said presser element to connect it with said support, and also adapted to swing clear of 15 said element, and pressure mechanism adapted for co-operation with said support.

8. An apparatus for subjecting articles to pressure, comprising a conveyor composed of movably connected links, a rotatable drum engaged 20 by said conveyer and adapted to bring the links successively into working position on the drum, and pressure mechanism in registry with the drum at such working position.

9. An apparatus for subjecting articles to pressure, comprising a conveyer chain composed of movably connected links, expandible cushions on said links, means for supplying a medium under pressure to said cushions, movable members arranged to engage said articles on the side opposite to the cushions, and bails pivoted to said links and arranged to engage said members, to hold articles mounted on said links, against the pressure exerted by the expanded cushions. 25

30 10. An apparatus according to claim 9, in which a compressor is provided to supply air under pressure to the cushions, and in which a heater is located in the neighborhood of the path taken by the air on its way from the compressor to the cushions. 35

40 11. An apparatus according to claim 9, in which a compressor forces air into the cushions and has its suction port likewise connected with the cushions, with the interposition of relief valves, to circulate the air. 45

45 12. An apparatus according to claim 9, in which a compressor is provided to supply air under pressure to the cushions, the latter having outlets controlled by relief valves, and in which the delivery connection of the compressor to the 50 cushions is controlled by individual valves which in one position connect the respective cushion with the supply of compressed air, and in another position with the atmosphere.

55 13. An apparatus for subjecting articles to pressure, comprising a traveling conveyer adapted to support the articles to be treated, electric heating means carried by said conveyer to heat said articles, and co-operating electric contacts mounted respectively on said conveyer and on stationary supports, to supply said heaters with electric current whether the conveyer be in motion or stationary, and mechanism for exerting pressure on articles supported by said conveyor. 60

65 14. An apparatus for subjecting articles to pressure, comprising a rotatable drum, a plurality of article carriers engaging said drum and movable therewith, and stationary pressure mechanism arranged in registry with the uppermost portion of the drum to co-operate with said article carriers when they reach said uppermost portion, said carriers being hingedly connected with each other after the manner of chain links. 70

75 15. An apparatus for subjecting articles to pressure, comprising a conveyor having supports

for such articles, expandible cushions on the conveyer, and a compressor, carried by the conveyer, for supplying a medium under pressure to said cushions.

5. 16. In combination, a shoe press having a pad, means for clamping a shoe against said pad, and a flexible elongate conveyor for holding said press during the loading operation in a manner such that the upper face of the press is longitudinally inclined downwardly toward the operator, to facilitate loading and unloading thereof.

10. 17. In combination, a shoe press having a pad, means for clamping a shoe against said pad, and a flexible elongate conveyor for holding said press during the loading operation, said conveyor having a surface inclined downwardly toward the operator whereby the face of the press is similarly inclined, to facilitate loading and unloading thereof.

15. 18. In a machine of the class described, in combination, a pair of spaced, parallel, tilted drum members, a flexible conveyor mounted thereon, a plurality of shoe presses mounted on said conveyor and adapted to be moved past a loading station thereby, each of said presses including a pad and means for clamping a shoe against said pad, said conveyor having a path such that as each press is presented to the loading station its pad and clamping means are downwardly inclined toward the operator.

20. 19. A machine of the class described, including, in combination, a flexible conveyor having a plurality of shoe pressing means movable therewith, said conveyor providing a fixed upper traverse, fixed members disposed adjacent to said upper traverse and co-operating means on said pressing means and on said fixed members to confine and support said pressing means during movement thereof along said traverse.

25. 20. A machine of the class described, including, in combination, a flexible conveyor having a plurality of shoe pressing means movable therewith, said conveyor providing a fixed upper traverse, means for moving said conveyor, frame members disposed at the sides of said conveyor and carrying opposed tracks corresponding to said traverse, and means on each of said pressing means to engage said tracks to confine and support said pressing means during movement thereof along said traverse.

30. 21. A shoe press machine comprising, in com-

bination, a frame, an elongate flexible conveyor mounted for movement along said frame, a plurality of shoe pressing means movable with said conveyor, and means on said frame for confining part of the motion of said pressing means to a fixed rectilinear traverse.

35. 22. A machine of the class described, comprising, in combination, a frame, a carrier comprising a flexible elongate conveyor having an upper and lower traverse mounted on said frame, said conveyor having a plurality of shoe pressing means movable therewith, supporting portions associated with each of said pressing means and carried by said conveyor, said portions being disposed transversely with respect to said carrier and projecting laterally beyond the edges thereof, said pressing means being adapted to be moved through a circuitous path thereby, each of said pressing means including a pad and means for clamping a shoe against said pad, said carrier being tilted in a manner such that the pad and clamping means will be inclined downwardly from the horizontal toward the operator, and supporting means on said frame proximate to the upper and lower conveyor traverses which are adapted directly to engage and support the laterally projecting supporting portions of said shoe pressing means.

40. 23. In a sole pressing machine, an elongate frame having rotatable elements at the ends thereof, an endless carrier passing around said elements, said carrier having a plurality of shoe pressing means movable therewith in an endless path, each pressing means including supporting means and a pressure pad for clamping a shoe therebetween, said frame being arranged to support at least part of the weight of said pressing means, means for intermittently moving said carrier, and means for increasing the pressure between the pad and shoe of each pressing means at a given portion of the carrier path.

45. 24. In a sole pressing machine, an elongate frame having rotatable elements at the ends thereof, an endless carrier passing around said elements, said carrier having a plurality of shoe pressing means movable therewith in an endless path, each pressing means including shoe supporting means and an inflatable pad, means for intermittently moving said carrier, and means for inflating each pad at a given portion of said carrier path.

OTTO HABICHT.
